FROST MEASURING DEVICE

Ernest J. Fields, Erie, Pa., assignor to General Electric Company, a corporation of New York

Application January 17, 1939, Serial No. 251,341

8 Claims.

(Cl. 62—1)

My invention relates to refrigeration and more particularly to means for measuring the accumulation of frost on the surface of the cooling unit associated with mechanical refrigerating apparatus.

It is generally known that the excessive accumulation of frost or ice on the cooling unit or evaporator of a mechanical refrigerator decreases the efficiency of refrigeration. Customarily, the purchaser of a mechanical refrigerator of the domestic type is informed by the vendor or by means of printed instructions of the necessity of defrosting the cooling unit at intervals according to the rapidity and amount of frost accumulation. However, it is impossible for the user of the refrigerator to correctly determine the proper time for defrosting merely by glancing at the cooling unit so that frequently the equipment is operated at low efficiency with the consequent higher cost due to the heavy consumption of electric energy.

Accordingly, it is an object of my invention to provide a new and improved means for measuring the accumulation of frost on the cooling unit of a mechanical refrigerator which is simple, rugged and inexpensive to manufacture.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a fragmentary view of a refrigerator embodying my invention; Fig. 2 is an enlarged perspective view of a portion of the cooling unit shown in Fig. 1 illustrating the application of my invention; Fig. 3 is a view, partly in section, of a portion of the cooling unit and frost measuring device shown in Fig. 1 taken along the line 3—3 of Fig. 2; Fig. 4 is a schematic view, partly in section, illustrating the operation of the frost measuring device shown in Fig. 1; Fig. 5 is a modification of the frost indicating means illustrated in Figs. 1 to 4; and Fig. 6 is a view, partly in section, of the modification shown in Fig. 5 taken along the line 6—6 of Fig. 5.

In the embodiment of my invention illustrated in Figs. 1 to 4 of the drawing I have shown a refrigerator cabinet 10 having a cooling unit or evaporator 11 therein for cooling the food compartment 12 of the refrigerator 10. A frost measuring device 13 is associated with evaporator 11 and comprises a first or terminal member 13a

supported in relatively poor thermal exchange relationship with the evaporator as on the cooling unit 11 by a second member or support 14 of relatively low heat conductivity characteristics. 5 In use the operator need only glance at the terminal member 13a of measuring device 13. As will be seen by reference to Fig. 4, when the frost or ice layer builds out even with the member 13a, that is, to the position indicated by the numeral 16, the member 13a will be situated in the depression between adjacent ridges of ice 31 and concealed to an observer sighting along the surface of the unit adjacent to and in the vicinity of the member 13a or along the tops of 10 the ridges 31 of the ice layer 16, if the measuring device takes the form shown in the drawing, thereby apprising the operator or user of the necessity for defrosting the cooling unit 11.

20 In the modification illustrated in Figs. 5 and 6 a frost measuring device 33 of relatively low heat conducting material is shown as projecting outwardly from the cooling unit 11. With this arrangement the frost gradually builds outwardly along the frost measuring device 33 to the predetermined thickness at which point the frost layer conceals the measuring device 33, as previously described.

With reference to Fig. 1, the refrigerator 10 shown therein is of the domestic type having an 30 opening in the front wall in order to provide access to the food compartment 12, the opening being closed by a door 18. Shelves 19 are provided for more convenient storage of articles placed within the refrigerator. A temperature control switch 20 of any suitable type is illustrated on the front of the cooling unit 11 in order to permit adjustment of the operating temperature within the compartment 12 and also to permit defrosting of the cooling unit. The freezing compartment within the cooling unit 11 is closed by means of a door 21. Any suitable refrigerating system may be employed. I have shown in Fig. 2 a temperature control bulb 22 for determining the period of operation of the refrigerating machinery in a manner well understood in the art. Any suitable means may be utilized to maintain the control bulb 22 in good thermal contact with the surface of the cooling unit 11. I have illustrated the use of a control bulb clamp 23 suitably secured to the cooling unit 11 as by means of screws 24 threadingly engaging suitable threaded apertures in a suitable bracket 25. Bracket 25 may be secured to the cooling unit 11 in any suitable fashion as by welding, for example.

In the measuring device 13 illustrated in Figs. 1 to 4, the member 13a is shown as substantially cylindrical in shape and suitably supported from the clamp 23 by means of a support member 14. The support 14, illustrated as a wire in the drawing, should be made from a material of low heat conductivity in order to minimize the conduction of heat between the evaporator or cooling unit 11 and the terminal member 13a. Stainless steel has proved very satisfactory for the member 14 and may be secured to clamp 23 in any suitable manner as by welding. The terminal member 13a may be formed of any desired material. I prefer to use a material which is relatively non-heat conductive because the support member 14 may then be relatively short in length whereas if member 13a is relatively heat conductive, the low heat conductive support must be long enough to prevent any substantial transference of heat between member 13a and cooling unit 11. A molded plastic such as rubber or a molded phenolic or urea resin is satisfactory although other suitable materials will readily occur to those skilled in the art. It will be understood, however, that at least a portion of the measuring device must be made of a relatively non-heat conductive material. For instance, if both terminal member 13a and support 14 are made from metal which is relatively heat conductive, as aluminum, for example, the measuring device will begin to coat over with frost as soon as the cooling unit begins to frost over and the ice accumulation will build up as rapidly on the measuring device as on the cooling unit. If, however, the support 14 is relatively non-heat conductive, the heat conducted between member 13a and evaporator 11 is minimized and member 13a will not readily coat over with frost. In order to make the member 13a more readily visible to the user, I have found it desirable to color the member 13a as red, for example, in order to provide a contrast to the white background of the frost accumulation.

The evaporator or cooling unit 11 is illustrated as comprising a flat plate 26 and an outer corrugated plate 27 suitably secured thereto as by welding in order to provide passages 28 for the refrigerant circulated therein. As best shown in Figs. 2 and 3 the frost measuring device 13 may be placed between two corrugations 29 so that the user of the refrigerator may sight along the outer wall 30 of the cooling unit and when the accumulation of ice builds out to the thickness represented by dotted line 16 of the Fig. 4, for example, the frost measuring device 13 will be hidden in the depression or valley portion between the ridges 31 of the frost accumulation and the necessity for defrosting is determined.

It will be apparent that the frost measuring device 13 need not necessarily be placed between corrugations 29 but such arrangement is desirable because, when so placed, the indicating device 13 projects a minimum distance into the food space of the refrigerator 10 and is therefore less subject to blows from articles being moved within the compartment 12.

I have found that an accumulation of frost to a thickness of approximately $\frac{1}{4}$ to $\frac{1}{8}$ of an inch may be permitted without appreciably affecting the efficiency of refrigeration. Therefore, in the first described embodiment of my invention the side of member 13a which is farthest from the cooling unit 11 should be spaced that distance from the cooling unit 11.

Figs. 5 and 6 illustrate a modification of my invention in which the measuring portion or

member 33 of device 13 extends outwardly from the surface of cooling unit 11. The member 33 may be supported in any suitable fashion but has been illustrated as extending through an aperture in the control clamp 23 and as illustrated is held in place by means of a base 32 suitably secured to member 33 and clamped between the bracket 25 and the control clamp 23. Member 33 is made of a material having low heat conductivity characteristics. For example, a molded plastic, as rubber or a molded phenolic or urea resin, is satisfactory. With this arrangement, the extending portion 33 should be of such a length that it will become concealed from the view of an operator when the ice accumulation on the cooling unit 11 builds out to the aforementioned limits.

Other modifications will readily occur to those skilled in the art. For instance, the measuring device 13 may be of any shape, may be secured within the cabinet in any desired fashion and may be located in any desired place so long as the measuring device is positioned proximate a wall of the cooling unit so that it is indicative of the thickness of the ice accumulation.

While I have shown and described particular embodiments of my invention, I do not desire my invention to be limited to the particular constructions shown and described and I intend in the appended claims to cover all modifications within the spirit and scope of my invention.

What I claim as new and desire to secure by Letters Patent of the United States is:

1. In a mechanical refrigerator, a cooling unit, and a frost measuring device so arranged with respect to said cooling unit that an accumulation of frost on said unit of predetermined thickness will conceal said device from the view of the user sighting along the surface of said unit associated with said device whereby the user is apprised of the need for defrosting said unit, at least a portion of said device having relatively low heat conductivity characteristics in order to minimize the accumulation of frost on said measuring device.

2. In a mechanical refrigerator, a cooling unit, and means for determining the need for defrosting said unit, said means comprising a member spaced a predetermined distance from said cooling unit and disposed in relatively poor thermal exchange relationship with said unit, said member being positioned so that the accumulation of a predetermined thickness of frost on said unit will conceal said member from the view of an observer sighting along the surface of the unit associated with said device.

3. In a mechanical refrigerator, a cooling unit, and means to determine the need for defrosting said unit, said means including a first member in heat exchange relationship with and supported on said cooling unit, and a second member carried by said first member, said first member being formed of a material having relatively low heat conductivity characteristics, and said second member being spaced a predetermined distance from said cooling unit whereby said second member will be concealed from an observer facing the front of said unit and sighting along the surface thereof on which said determining means is supported when the frost accumulation on said cooling coil builds outwardly to a predetermined thickness.

4. In a mechanical refrigerator, a cooling unit having a corrugated exterior surface, and a device spaced a predetermined distance from said cooling unit and arranged between adjacent cor-

rugations of said unit whereby an accumulation of frost of a predetermined thickness on said corrugations will conceal said device from an observer sighting across the ice accumulated on the corrugations in the vicinity of said device, thereby determining the need for defrosting said unit, at least a portion of said device having relatively low heat conductivity characteristics in order to minimize the accumulation of frost on said device.

5. In a mechanical refrigerator, a cooling unit having a corrugated exterior surface, and means to determine the need for defrosting said unit, said means including a first member in heat exchange relationship with and supported on said cooling unit and being formed of a material having relatively low heat conductivity and a second member carried by said first member, said members being arranged in the space between two adjacent corrugations and said second member being disposed a predetermined distance from said cooling unit whereby said second member will be visible to an observer sighting across the ice accumulated on the corrugations in the vicinity of said device until the frost accumulation on said 10 cooling coil and corrugations builds out to and conceals said second member.

6. In a mechanical refrigerator, a cooling unit, and means for determining the need for defrosting said unit comprising a member of relatively 30 low heat conductivity material in heat exchange relationship with and supported by said unit and extending laterally therefrom whereby the accumulation of frost on said unit to a predetermined thickness will conceal said member from 35

the view of an observer facing the front of said unit and sighting along the surface thereof on which said determining means is supported.

7. In a mechanical refrigerator, a cooling unit, and means for determining the need for defrosting said unit comprising a member positioned proximate a wall of said unit, a portion of said member being disposed a predetermined distance from said unit whereby the user is apprised of the need for defrosting said unit when the accumulation of frost has built out approximately even with said portion as determined by an observer sighting along the surface thereof in the vicinity of said member, said portion being formed from a material having relatively low heat conductivity characteristics in order that said portion will not readily accumulate frost thereon.
